DESIGN FOR A PIN OR SIMILAR ARTICLE

Marcel Boucher, New York, N. Y.

Application February 15, 1940, Serial No. 90,274

Term of patent 3½ years

To all whom it may concern:

Be it known that I, Marcel Boucher, a citizen of the United States, residing in New York city, in the county of New York and State of New York, have invented a new, original, and ornamental Design for a Pin or Similar Article, of which the following is a specification, reference being had to the accompanying drawing, forming part thereof.

Fig. 1 is the plan view of a pin showing my new design;

Fig. 2 is an elevational side view of Fig. 1, and Fig. 3 is the rear view of Figs. 1 and 2.

I claim:

The ornamental design for a pin or similar article, substantially as shown.

MARCEL BOUCHER.
